(57) **CLAIM**

The ornamental design for a neck and head support, as shown and described.

DESCRIPTION

FIG. 1 is a top perspective view of a neck and head support showing our new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof;

FIG. 8 is a rear view thereof;

FIG. 9 is a deflated view thereof; and,

FIG. 10 is an inflated view thereof.

The environment portions of the figures shown in broken lines form no part of the claimed design.
